UNITED STATES PATENT OFFICE.

EDWARD H. HUXLEY, OF BRISTOL, RHODE ISLAND, ASSIGNOR TO NATIONAL INDIA RUBBER COMPANY, OF BRISTOL, RHODE ISLAND, A CORPORATION OF RHODE ISLAND.

DESIGN FOR A RUBBER MAT.

42,327.

Specification for Design.

Patented Mar. 19, 1912.

Application filed July 22, 1911. Serial No. 640,038. Term of patent 14 years.

To all whom it may concern:

Be it known that I, EDWARD H. HUXLEY, a citizen of the United States, residing in Bristol, county of Bristol, State of Rhode Island, have invented a new, original, and ornamental Design for Rubber Mats, of which the following is a specification, reference being had to the accompanying drawing, forming a part thereof, in which the figure is a plan view of a rubber mat, showing my new design.

I claim:

The ornamental design for rubber mat, as shown.

EDWARD H. HUXLEY.
